(57) **CLAIM**

The ornamental design for a pickleball racket bumper, as shown and described.

DESCRIPTION

FIG. 1 is a front perspective view of a first embodiment of a pickleball racket bumper showing our new design; FIG. 2 is a front view thereof;

FIG. 3 is a rear view thereof;

FIG. 4 is a top view thereof;

FIG. 5 is a bottom view thereof;

FIG. 6 is a left side view thereof;

FIG. 7 is a right side view thereof;

FIG. 8 is a cross sectional view thereof, taken along line 8-8 of FIG. 4;

FIG. 9 is a front perspective view of a second embodiment of a pickleball racket bumper showing our new design;

FIG. 10 is a front view thereof;

FIG. 11 is a rear view thereof;

FIG. 12 is a left side view thereof;

FIG. 13 is a right side view thereof;

FIG. 14 is a top view thereof;

FIG. 15 is a bottom view thereof;

FIG. 16 is a cross sectional view thereof, taken along line 16-16 of FIG. 14;

FIG. 17 is a front perspective view of a third embodiment of a pickleball racket bumper showing our new design;

FIG. 18 is a front view thereof;

FIG. 19 is a rear view thereof;

FIG. 20 is a top view thereof;

FIG. 21 is a bottom view thereof;

FIG. 22 is a left side view thereof;

FIG. 23 is a right side view thereof; and,

FIG. 24 is a cross sectional view thereof, taken along line 24-24 of FIG. 20.

The lighter line-weight broken lines on the drawings form no part of the claimed design. The heavier line-weight dotted lines represent boundary lines and form no part of the claimed design.

1 Claim, 18 Drawing Sheets
